UNITED STATES PATENT OFFICE

2,431,239

JOURNAL BOX FOR RAILWAY CARS

James W. Gallagher, Prospect Park, Pa.

Application October 2, 1943, Serial No. 504,699

6 Claims. (Cl. 308—50)

1

The object of the invention is to provide means for the ready detection of so-called "hot boxes" in journal bearings for axles of freight and passenger railway cars. Journal boxes applied to freight cars are usually lubricated by means of oiled waste. Journal boxes of passenger cars usually comprise roller bearings and are lubricated from an oil reservoir in which the axle revolves. When, owing to the development of certain abnormal conditions, these journal boxes become so highly overheated as to develop a "hot box," continued rise in temperature causes the ignition of the oil or oil waste, thereby, by destroying the lubrication, creating a serious and dangerous condition.

It has been proposed to ventilate hot boxes by providing in the cover openings for admission and release of atmospheric air. While such openings have the advantage of enabling, at a train stop, the ready detection of a hot box by visual inspection through such openings, the objections thereto overbalance their advantages. Any air inlet openings in the journal box not only admit dust and dirt, but induction of air is attended with a supply of oxygen that promotes combustion and intensifies, or even creates, the "hot box" condition. Experience has shown the advisability of as far as possible sealing the journal box against admission of air and therefore of sealing the inside of the journal box from visual inspection, so that timely discovery of a "hot box" frequently is not made.

The object of my invention is to retain, as far as possible, the normal sealing of a journal box while at the same time allowing the detection of a "hot box" as speedily as possible and before it reaches a dangerous or destructive stage.

Two of different possible developments are shown in the drawings, in which—

Fig. 1 is a front view, and Fig. 2 a longitudinal sectional view, of a journal box embodying my invention.

Fig. 3 is a section view, and Fig. 4 an outside face view, of a journal box lid or closure embodying my invention in another specific form.

In the embodiment shown in Fig. 1, *a* is the axle, *b* the bearing therefor, *c* the enclosing box body and *d* the lid therefor, the latter having end hooks *e*, *e* which engage a rod *f* carried by a lug *g*, secured to the box body. By means of a heavy leaf spring *i*, the lower end of which is secured to the outer face of the lid *d* and the upper free end of which engages the lug *g*, the lid is held tightly in place, while its ready opening is permitted. A journal box of this type is

usually stuffed with oiled waste to afford adequate lubrication for the axle. The specific construction of journal box shown is only one of several types in actual use and is commonly applied to freight cars. In some cases, particularly on passenger cars, the axle turns in roller bearings and the lid is bolted to the box body. Such alternative constructions of journal boxes need not be shown or in detail described, since the specific construction of the journal box forms no part of my invention.

In Fig. 1, the lid *d* is shown as provided with two openings *h* in the same horizontal plane near opposite side ends of the lid. The edge of the lid surrounding and forming each opening is upset or flanged outward at *k* to overlie the edges of a plate *m*, which extends in the same plane as the lid and completely closes the opening. Between the plate *m* and the marginal portion of the lid *d* is a gasket *o*. To hold the plate *m* in position against the flange *k* a fusible metal strip *p* overlies, or spaced-apart fusible metal pieces overlie, and solder the joint between the edge of the plate and the edge of the lid *d* surrounding and forming the opening therein.

There may be applied to the outer face of the lid, adjacent the openings therein, wings *x*, *x*. These may be so applied by providing them with flanges *x'* and securing these flanges to the face of the lid by spot welding.

Under normal conditions, the temperature within the journal box is substantially below that required to fuse the strip *p*. When, however, there is an abnormal rise in temperature within the journal box due to any cause, but long before the temperature rises to the extent necessary to burn out the lubricant, and therefore while the temperature is still below that required to produce a dangerous "hot box" condition, the fusible strip melts and the closure plate *m* is released and drops down into the bottom of the box. The immediate effect is to allow atmospheric air to enter the journal box. Before any initial burning reaches a dangerous stage, smoke forms in the interior of the journal. The air admitted to the journal box enters in the form of a strong current and drives the smoke out of the opening or openings formed by prompt release of the closure plate *m*. It is of pronounced advantage to provide the two openings shown in Figs. 1 and 4, so that the air enters one opening and is expelled, with the smoke, through the other, as indicated by the arrows in Fig. 1.

It is customary, in the operation of trains, for the train crew to make visual inspections of the

entire train while in transit, particularly while it is proceeding along a curve, at which time all the cars on the inside of the curve are in line of vision, and any "hot box" condition will be observable. Unfortunately, however, in journal boxes now in use, such condition is not revealed until the fire has reached an actually dangerous stage, due to the fact that the journal box is sealed against admission of air. In my invention, as above stated, the "hot box" condition is observable at an early stage, before an actually dangerous or destructive condition has developed; and, moreover, it is observable while the train is traveling on a straight track.

The opening for the admission of air and the discharge of air and smoke must be of a size that should not be substantially smaller than is shown in the drawings. An opening comparable to a pin hole and sealed by a fusible plug would be inoperative. On the other hand, it is of no importance to provide openings large enough to enable necessary repairs to be made. Such repairs, obviously, will be made after swinging up the lid, in order to allow free and unobstructed access to the interior of the journal box.

After the discovery of the "hot box" condition the train will, of course, be brought to an immediate stop and the necessary repairs made before starting the train.

It is of distinct advantage to provide two openings, as shown in Figs. 1 and 4, so as to provide for a continuous and unobstructed "current" of air, thereby insuring the quickest, most free, and most complete, discharge of the smoke.

The wings *x* are also of pronounced advantage, since they function to direct the smoke for a considerable distance in a stream at nearly right angles to the direction of extension of the car, thus more nearly insuring early observation. Such a warning signal will not be confused with any slight smoke arising from a hot wheel caused by stuck brakes. If no observation of the train in transit should be made, the most casual examination of the journal box by the inspector at the next stop discloses the opening or openings in the lid. Usually the "hot box" will even then be detected before it develops to a dangerous or destructive stage. But there is no insurance, especially on a long run between stops, that the "hot box" may not reach this stage before the train arrives at a scheduled stop. No means for guarding against the burning out and destruction of axle bearings can be considered acceptable that affords only relative protection. The protection, to be acceptable, must provide against all foreseeable conditions.

It is true that, once the closure or closures for the opening or openings are removed, the journal box will be no longer sealed against the temporary admission of dust, dirt, water and other foreign material. This sealing is, of course, desirable, and even necessary, in normal operation and is provided for in my improved journal box. However, the exclusion of such foreign material becomes of no importance whatever in comparison with the importance of a prompt and accurate detection of an incipient hot box.

In the modification shown in Figs. 3 and 4, the same reference letters are applied to the same parts. Instead of securing the plate *m* in place by fusible metal overlapping the joint between the plate *m* and the lid *d*, the plate is held in place against the gasket *o* by means of a spring *s* surrounding a bolt *r* secured to the plate *m* and extending through a yoke *t*, the lower end of

which is loosely pivoted on a bolt *u* secured to the lid below the opening therein and the upper end of which is sleeved on a stud *v* secured to the lid above the opening therein. The upper end of the yoke *t* is held on the stud *v* by means of a fusible pin *w*. The spring *s*, confined between the yoke *t* and plate *m*, holds the latter, under normal conditions, in position to securely close the opening in the lid; but when the temperature within the journal box rises above the melting point of the fusible pin *w*, the spring *s* swings the yoke *t* inward on its loose pivotal connection on bolt *u* until the upper end of the yoke rides off the end of the stud *v*, whereupon the yoke by gravity swings down on its pivoted lower end into the position shown in dotted lines in Fig. 3, carrying with it the spring *s*, the bolt *r* and the plate *m*.

It is preferred to apply the detector shown in Figs. 1 and 2 to the type of journal boxes commonly used on freight cars and to apply the detector shown in Figs. 3 and 4 to the type of journal box commonly used on passenger cars, although either type of detector is operative when applied to any type of journal box.

What I claim and desire to protect by Letters Patent is:

1. A railway journal box including the axle, the bearing, the box body and its lid, the lid containing an opening of substantial area, a plate applied to said opening, means including fusible material adapted to hold the plate in position to close the opening while the temperature within the box is below that required to fuse said material but which, upon fusion due to rise in temperature, releases such plate from closing position, and a wing extending outward and contiguous to said opening and extending therefrom at a substantial angle to the plane of the opening and adapted to assist entrance of atmospheric air to the journal box through said opening and adapted also to direct the expulsion of smoke largely through said opening in a direction outward from the journal box to facilitate its ready detection.

2. A railway journal box including the axle, its bearing and the box body, two openings of substantial area in the lid, plates, one applied to each opening, means including fusible material adapted to hold each plate in position to close the corresponding opening while the temperature within the box is below that required to fuse said material but which, upon fusion due to rise in temperature, releases such plate from closing position, said openings being located on opposite sides of the center of the lid and in substantial horizontal alignment with each other, two wings extending outward adjacent the respective openings, each wing extending along that side of the corresponding opening which is nearest the center of the lid, one of said wings functioning to assist entry of atmospheric air to the journal box largely through one of said openings and the other functioning to direct the expulsion of smoke largely through the other opening in a direction outward from the journal box to facilitate its ready detection.

3. A railway car journal box as defined in claim 1, in which said plate is located inside said lid and overlaps said opening and in which said fusible material is applied to the inside of the lid and closure plate and overlaps the joint between them.

4. A railway car journal box as defined in claim 1 in which the margin of the lid surrounding said

opening is provided with an outwardly extending flange against which the closing plate is confined, the closing plate thereby extending in the same plane as the lid, and in which said fusible material is applied to the inside of the lid and closing plate and overlaps the joint between them.

5. A railway car journal box as defined in claim 1 in which the means for holding the plate in closing position comprises a bar within the box, a spring confined between said bar and plate and holding the plate against the lid in position to close the opening and means to hold the bar in position to maintain the spring in tension, said means including material adapted to be fused at a predetermined temperature to thereby release the bar from its holding position.

6. A railway car journal box as defined in claim 1 in which the means for holding the plate in closing position comprises a bar loosely pivoted at one end to the inside of the lid and at the other end sleeved on a stud, a spring confined

between the bar and the plate and holding the plate against the lid in position to seal the opening, and fusible material adapted to hold said other end of the bar on the stud but adapted 5 when fused to allow the spring to force said other end of the bar off the stud, the bar being thereby free to swing on its pivot, thereby moving said plate out of register with said opening.
